UNITED STATES PATENT OFFICE

ALFRED F. JACKSON, OF ATTLEBORO, MASSACHUSETTS, ASSIGNOR TO LEWIS R. SMITH RECEIVER FOR THE APCO MOSSBERG CORPORATION, A CORPORATION OF MASSACHUSETTS

ENGINE HOOD ANTIRATTLING DEVICE

Application filed May 15, 1931. Serial No. 537,607.

My present invention relates to anti-rattling devices, and more particularly to a novel and improved anti-rattling device for use in connection with the engine hood and engine hood hold-down clamps of motor vehicles.

In many present day automobiles, the anti-rattling bumper comprises a rubber slug riveted to the side of the engine hood adjacent to the bottom thereof, and interposed between the hood and the hood hold-down clamp. These bumpers are subjected to considerable wear and rough usage, and very frequently split, or become pulled away from the rivet during use. This results in a great deal of inconvenience to the motorist, requiring the removal of the rivet, as by shearing, and the replacing of an entire new bumper and rivet.

An important object of the present invention, therefore, resides in the provision of an anti-rattling device or bumper which may be readily attached in place of a worn or broken bumper, by being snapped over the original rivet.

Another object of the invention resides in the provision of metallic means to take up and absorb the wear and vibrations between the rivet and the bumper.

A still further object of the invention resides in the provision of spring means to permit facile attachment of the device and also to prevent inadvertent removal thereof.

Other objects and features of the present invention, details of construction, combinations of parts, and advantages, will be herein-after more fully pointed out, described and claimed.

Referring to the drawings, illustrating a preferred embodiment of the present invention,

Fig. 1 is a side elevation of my novel anti-rattling device in position;

Fig. 2 is a front elevation of the device;

Fig. 3 is a cross sectional view, on an enlarged scale, of the bumper positioned on the original rivet; and

Fig. 4 is a cross sectional view on the line 4-4 of Fig. 3.

Referring now to the drawings, for a particular description of the invention, 1 designates a conventional automobile engine

hood having the rounded bottom edge 2 and having clamp engaging ears, one of which is illustrated at 3 secured to the hood by the rivets 4. On the apron 5 is fixed a bracket 6 by rivets 7, this bracket carrying a pivot pin 8 on which is pivotally mounted the housing 9 within which is slidable the stem 10 of the hood hold-down clamp 11, a finger hold 12 being provided. The hold-down clamp 11 is held in normal clamping position by means of a coiled spring within the housing 9, but as this is standard construction and constitutes no part of the present invention, the same is not illustrated or described in detail herein.

13 designates the rivet which holds the original bumpers to the engine hood, and this rivet is illustrated with my novel anti-rattling bumper positioned thereover.

My novel device comprises a bumper 14, preferably of rubber, having a concaved outer face 15 with a central boss or plug 16. This bumper 14 is provided with a recess 17 and with an undercut groove 18. Positioned in the groove 18 is an annular washer 19, and also located in said groove is the flange 20 of a retainer 21. It will be apparent, from a glance at the drawings, that the washer 19 and flange 20 are of greater diameter than the diameter of the recess 17, thus insuring that the bumper 14 will not inadvertently be separated from either the flange 20 or washer 19.

Interposed between the washer 19 and retainer 21 is a split spring ring 22, the normal diameter of this split ring being slightly less than the diameter of the head 23 of the rivet 13.

It will also be apparent, from a glance at the drawings, that my novel device is extremely simple to apply, it being merely necessary to engage the head 23 of the rivet 13 with the spring ring 22, and effect a pressure thereagainst. This will effect a spreading or opening of the spring ring 22 until said ring has passed the edge or rim of the head 23, whereupon the spring ring 22 will return to normal contracted position, at which time it will be behind the head 23, as

clearly illustrated in Fig. 3, and will thus firmly unite the device to the hood 1.

The wall 24 is preferably of greater height than the normal distance between the outer surface of the hood 1 and the flange 20 when the device is in the position illustrated in Fig. 3. This will result in a spring tension being exerted outwardly on the retainer 21 and ring 22, maintaining the same in engagement with the head 23 of the rivet 13.

When the device is attached and the hold-down clamp 11 is in engagement with the ear 3, the housing 9 will bear across the face of the bumper 14, and will have a resilient seat thereagainst partly because of the material of which the bumper is made, and partly because of the configuration of said face.

My novel device is simple and economical to manufacture, and very simple to apply, requiring but a slight fraction of time to install.

The advantages and benefits of my anti-rattling device will be instantly apparent to those skilled in this art, as well as to automobile owners, and since I believe that this device is novel, I have claimed the same broadly in the present application.

While I have necessarily described my present invention somewhat in detail, it will be appreciated that I may vary the size, shape, and arrangement of parts, within reasonably wide limits without departing from the spirit of the invention.

My invention is further described and defined in the form of claims as follows:

1. An anti-rattling device of the kind described, comprising a resilient bumper having a recess therein, an undercut groove at the inner end of said recess, a retainer seated in said groove, and a spring ring confined by said retainer.

2. An anti-rattling device of the kind described, comprising a resilient bumper having a recess therein, an undercut groove at the inner end of said recess, a retainer seated in said groove, an annular washer also seated in said groove, and a spring ring interposed between said washer and said retainer.

3. An anti-rattling device for attachment to the original bumper rivet of an engine hood, comprising a bumper of resilient material, said bumper having a recess therein and having an undercut groove at the inner end of said recess, an annular washer seated in said recess, a retainer seated in said recess, and a spring ring interposed between said washer and said retainer and adapted to be snapped over the head of said original rivet to hold said device in position.

4. An anti-rattling device for attachment to the original bumper rivet of an engine hood, comprising a bumper of resilient material having a convolute outer face, said bumper having a recess therein and having an undercut groove at the inner end of said

recess, an annular washer seated in said recess, a retainer seated in said recess, and a spring ring interposed between said washer and said retainer and adapted to be snapped over the head of said original rivet to hold said device in position.

5. An anti-rattling device for attachment to the original bumper rivet of an engine hood, comprising a bumper of resilient material, said bumper having a recess therein and having an undercut groove at the inner end of said recess, an annular washer seated in said recess, a retainer seated in said recess, and a spring ring interposed between said washer and said retainer and adapted to be snapped over the head of said original rivet to hold said device in position, the wall of said bumper surrounding said recess being of greater height than the normal distance between the outer surface of said engine hood and said retainer when said device is in attached position, whereby said spring ring is resiliently held against the rear edge of said rivet head.

6. An anti-rattling device for attachment to the original bumper rivet of an engine hood, comprising a bumper of resilient material having a convolute outer face, said bumper having a recess therein and having an undercut groove at the inner end of said recess, an annular washer seated in said recess, a retainer seated in said recess, and a spring ring interposed between said washer and said retainer and adapted to be snapped over the head of said original rivet to hold said device in position, the wall of said bumper surrounding said recess being of greater height than the normal distance between the outer surface of said engine hood and said retainer when said device is in attached position, whereby said spring ring is resiliently held against the rear edge of said rivet head.

In testimony whereof, I have signed my name to this specification.

ALFRED F. JACKSON.
